OIL CAN DISPLAY CABINET

Harvey J. Smith, Greensboro, N.C., assignor to Modern Metal Products Company, Inc., Greensboro, N.C., a corporation of North Carolina

Filed May 28, 1964, Ser. No. 80,193

Term of patent 14 years

(Cl. D80—11)

FIG. 1

FIG. 2

FIG. 3

FIG. 4

FIG. 1 is a front perspective view of an oil can display cabinet, embodying my new design;

FIG. 2 is a right side elevational view thereof, the left side being essentially flat and plain;

FIG. 3 is another perspective view thereof, the cover being in a partially open position; and

FIG. 4 is a top plan view thereof.

The broken line showing of oil cans in FIG. 3 is for purposes of illustration only. The rear of the display cabinet is substantially identical to the front view as shown in FIG. 1.

I claim:

The ornamental design for an oil can display cabinet, as shown and described.
